Primary Examiner — Cynthia M. Chin

(57) **CLAIM**

The ornamental design for a toy as shown and described.

DESCRIPTION

FIG. 1 is a front, right and top perspective view of a toy showing my new design;

FIG. 2 is a rear, right and bottom perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof;

FIG. 8 is a bottom plan view thereof; and,

FIG. 9 is an enlarged view of a portion labeled as "9" on FIG. 1.

The long dash-short dash broken lines depict enlargement boundaries that form no part of the claim. The evenly broken lines illustrate portions of the toy that form no part of the claimed design.

1 Claim, 9 Drawing Sheets
